DESIGN FOR A MITTEN

John De Grand, Gloversville, N. Y.

Application August 7, 1942, Serial No. 107,840

Term of patent 3½ years

To all whom it may concern:

Be it known that I, John De Grand, a citizen of the United States of America, residing at Gloversville, in the county of Fulton and State of New York, have invented a new, original, and ornamental Design for a Mitten, of which the following is a specification, reference being had to the accompanying drawing, forming a part thereof.

In the drawing:

Figure 1 is a front elevational view of a mitten embodying my new design,

Figure 2 is a side elevational view of the same, and

Figure 3 is a rear elevational view of the same on a reduced scale.

The characteristic feature of my design resides in the combination on the mitten disclosed of the specific back portion which is stitched and pinked as shown.

I claim:

The ornamental design for a mitten, as shown and described.

JOHN DE GRAND.
